UNITED STATES PATENT OFFICE.

FRANK G. MARBACH, OF MEDINA, OHIO.

RATCHET TAP AND NUT WRENCH.

No. 823,610

Specification of Letters Patent.

Patented June 19, 1906.

Application filed February 12, 1906. Serial No. 300,586.

To all whom it may concern:

Be it known that I, FRANK G. MARBACH, a citizen of the United States, residing at Medina, in the county of Medina and State of Ohio, have invented certain new and useful Improvements in Ratchet Tap and Nut Wrenches; and I do declare that the following is a full, clear, and exact description of the invention, which will enable others skilled in the art to which it appertains to make and use the same.

My invention relates to improvements in ratchet-wrenches and other tools; and the invention consists in the construction and combination of parts, substantially as shown and described, and particularly pointed out in the claims.

In the accompanying drawings, Figure 1 shows a longitudinal elevation of wrench with the ends in section and the middle broken away, but in whole lines otherwise. Fig. 2 is a perspective view, partially in plan, of the ratchet-head in the top of the tool. Fig. 3 is a bottom or lower end view of the tool, and Fig. 4 is a perspective view of the connecting member for the tool with the wrench proper. Fig. 5 is a view of a modification of the tool as a whole, and Fig. 6 is a vertical section of Fig. 5 at right angles to Fig. 5.

In the device as thus shown, A represents the barrel of the tool, which is tubular or cylindrical and provided with a solid lower end having an angular and preferably square hole *a* through the same, by means of which engagement is made with the wrench B by the intermediate part C. The said wrench in this instance is shown as having a socket end *b* for engagement by part C and constructed at its opposite end to seat over or upon a nut to rotate the same, and part C is a rigid rectangular connecting-piece which serves to operatively unite wrench B with the body A through hole *a*, a spring *c* on the side of said connecting-piece serving to hold the piece in the said body and to engage tool B therewith. I might of course engage the wrench or other tool directly in hole *a* of the barrel or body; but the present arrangement is deemed best, for the reason that the tools used such as are found in the market with socketed shanks, as in this case, and by the use of union-piece C, I am enabled to employ any and all tools having such sockets and which are adapted to be used by rotation, whether for one purpose or another, the use

itself not being material. However, the tool as thus shown and constructed is more especially designed for use in places which are wholly inaccessible to wrenches as ordinarily made and which require room round about the nut to rotate them.

By my present construction a nut can be reached at any point however encumbered its surroundings may be, if the tool can be projected thereto. Of course in its broadest sense I do not claim a tool having such capabilities to be wholly new; but I am not aware that the present construction as claimed herein has ever before been known or used.

Referring now to the ratchet portion of the tool I show two separate and distinct members D and E, associated with the upper end of tube A. Thus the member D is essentially the ratchet member, having a ratchet-head *d*, with right-angled channels 2 on its top and locked in main tube A by transverse pin 3, which fixes said parts rigidly together. The said member D projects above or beyond the end of tube A and has a reduced portion or neck 4 next beneath head *d* of sufficient depth to give sleeve or cap E longitudinal movement to effect engagement and disengagement of the ratchet mechanism. To effect said engagement, the cap E is provided with cross rod or bar 5 beneath its own head 6, which is adapted to engage in either of the transverse channels 2 in ratchet-head *d*, according to its position and relation to said head, and engagement is made by pressing cap E inward and disengagement by drawing it outward, and a short set-screw 7 in the cap enters the annular channel or groove 4, forming the neck of member D, and limits the movements of cap E in respect to said member.

An operating-handle II is slidably engaged at right angles through head 6 of the ratchet-controlling cap and has a reduced stem portion *h*, with a headed screw 8 in its end, adapted to confine the stem in said cap, but leaving it free to be moved back and forth therein within the limits of its own length. This gives the operator full control of the tool and more or less rotary leverage, as he may need, and the tool is so constructed in point of length that it can be inserted and used in otherwise wholly inaccessible places. To this end the body or tube A may have a greater or less length and may also be made in different lengths.

In Fig. 5 a chuck is shown which involves

the same principle of construction in the main, having a body A', a threaded or screw-engaging ratchet member D' therein, provided with a ratchet-head d', as in Fig. 2, and 5 channels therein adapted to be engaged by handle H' through its flat-sided central portion h'. The cap or sleeve E' is slideable up and down within limits determined by setscrew 9 extending into the annular space beneath ratchet-head d', as with screw 7 in Fig. 1. In this case the handle H' is not movable lengthwise, though it might be, and it takes the place of both handle H and fixed cross rod or bar 5 in Fig. 1.

15 What I claim is—

1. In ratchet-tools, a barrel and a ratchet-head at the upper end of said barrel, and a cap sleeved over said head and the end of the barrel and provided with a cross-piece internally adapted to engage said head.
2. A ratchet-tool having a suitable barrel, a ratchet member fixed in said barrel and extending above the same, a cap slideably and

rotatably engaged with said ratchet member, a cross part in said cap adapted to engage 25 said ratchet member and means to rotate said parts fixed in said cap.

3. A ratchet-tool having a body and ratchet mechanism connected therewith, said mechanism comprising a ratchet-head having open slots at right angles across its top, a slideable sleeve on said body and means to engage said ratchet projecting through said sleeve.

4. A ratchet-tool having a body and a 35 ratchet connected with the top thereof, a sleeve slideably engaged over the said ratchet and provided with a handle at its top and a device in said sleeve to engage said ratchet.

In testimony whereof I sign this specifica- 40
tion in the presence of two witnesses.

FRANK G. MARBACH.
